[57] CLAIM

The ornamental design for an feeder, substantially as shown and described.

DESCRIPTION

FIG. 1 is a right side elevational view of an feeder showing my new design, the left side being a mirror image of the right side shown;

FIG. 2 is a front elevational view thereof;

FIG. 3 is a rear elevational view thereof;

FIG. 4 is a top plan view thereof; and

FIG. 5 is a bottom plan view thereof.

FIG. 1

FIG. 2

FIG.3

FIG.4
